United States Patent Office.

J. S. CARR, OF ALLIANCE, OHIO.

Letters Patent No. 97,878, dated December 14, 1869.

IMPROVEMENT IN MACHINE FOR DRESSING MILLSTONES.

The Schedule referred to in these Letters Patent and making part of the same.

To all whom it may concern:

Be it known that I, J. S. CARR, of Alliance, in the county of Stark, and State of Ohio, have invented new and useful Improvements in Machines for Dressing Millstones; and I do hereby declare that the following is a full, clear, and exact description of my invention, reference being had to the accompanying drawings, forming a part of this specification, and to the letters of reference marked thereon, of which drawings—

Figure 1 is an elevation of my improved machine.
Figure 2 is a plan of the same.

The nature of my invention consists in so constructing a machine for dressing millstones, as that the rotation of the shaft, which imparts a reciprocating movement to the pick, shall also cause a curvilinear movement of said pick, as is hereinafter shown, whereby I am enabled to dress the stone with a curvilinear dress, in a cheap and effectual manner, by a mechanical operation which involves but little skill on the part of the operator, the principal care being in placing the machine on the stone, in a proper position for cutting the grooves in the correct place to form the desired dress.

To enable others skilled in the art to make and use my invention, I will proceed to describe its construction and operation.

N represents the platform of the machine; the front end of which is supported by a roller, Z, as shown.

This roller is arranged in arms d d, and has the ratchet-wheel Y on the end of one of its axle-pins, and the lever X, with pawl e, is also pivoted on said axle-pin, so that by raising the lever X, the roller Z is made to revolve, and the machine is moved forward.

The circular toothed gear-rim M is fastened on the platform N, and inside of it is arranged the turn-table O, which is secured in position by the axial-bolt P, as shown in fig. 1.

In this turn-table O are secured the standards A A, (the front one of which is broken away in fig. 1, to show the arms of the pick-shaft,) which are united at their upper ends by the cross-bar B, (not shown in fig. 2,) and in front of these standards A are secured the pick-shaft standards W W, as shown.

The pick-shaft S is pivoted, between the standards W W, by the pivot-bolts f f, which are clamped in any desired position by the screws g g.

The pick-arm Q, which has the pick R secured in a hole near its outer end in any suitable manner, is secured in a slot in the pick-shaft by the clamp-screw e, so that by loosening said screw, the pick-arm may be moved in or out, thus changing the distance between the pick and pick-shaft, and, consequently, the radius

of curvature of the groove formed by the pick, as desired.

The recoil-spring V is fastened to a block on the turn-table O, in such a manner as to cause the pick-arm Q to strike on it at each blow, thus insuring an immediate recoil of the pick after each blow, and preventing a "dead-stroke" of the pick, which is liable to break the pick and injure the stone.

The tilting-arm T and the spring-arm U are attached to the pick-shaft S, as shown, and a cord or chain, D, is secured to the end of the spring-arm U, the other end of said cord or chain being secured to the end of the lever C, which is pivoted by a bolt, a, on the standard A, as shown.

The shaft H is arranged in boxes, k k, secured on the standards A A, and has the crank I secured at its end, as shown.

On this shaft is secured the fly-wheel J, provided with one or more tappets, b b, and the worm h, as shown in fig. 2.

The shaft F is arranged so as to move up and down, and to turn in the arms l E, which are secured to the standard A, (the arm E being removed in fig. 2, for sake of clearness in drawing,) and it is supported at the proper height by a collar, K, which rests on the arm l.

The pinion L is secured at the lower end of the shaft F, and meshes into the fixed gear-rim M, as shown in fig. 1, and the worm-wheel G is also secured on this shaft, and engages with the worm h on the driving-shaft H, as shown in fig. 2.

The mode of adjusting and operating this machine will be easily understood after the foregoing description of its construction.

The pick R is so adjusted that the distance between it and the centre P of the turn-table O, shall be equal to the radius of curvature of the groove desired to be cut, and the machine is then placed on the stone, in such a position as that the pick R would move over the required groove in the stone.

Then, by turning the crank I, the revolutions of the fly-wheel J cause the tappets b b to force down the end of the tilting-arm T, which raises the pick R, and, as the tappet b slides off the arm T, the pick R is dropped, and a blow of the pick on the stone is attained.

In order to increase the force of this blow to any desired extent, it is only necessary to draw down the lever C, which tightens the chain D, and brings the action of the spring-arm U into play, as is readily seen.

The rotation of the worm h on the driving-shaft H, causes a slow rotation of the shaft F, which causes the

turn-table O to turn slowly around the axial-pin P, by reason of the action of the pinion L on the fixed gear-rim M, and this rotation of the turn-table causes the progressive movement of the pick R along the groove to be cut, as is readily seen.

By raising the shaft F, the pinion L and worm-wheel G may be thrown out of gear with the fixed gear-rim M and worm h, when the pick R can be turned to pick at any desired point, or by fastening the turn-table O so as to prevent its turning, the machine may be used for forming straight grooves, the forward movement of the machine, and, consequently, of the pick R, being obtained by the movement of the lever X, and its consequent action through the pawl c, on the ratchet-wheel Y and roller Z, as before described.

Having thus fully described my invention,

What I claim therein as new, and desire to secure by Letters Patent, is—

1. A machine for dressing millstones, constructed substantially as described, so that the rotation of the driving-shaft, which imparts a reciprocating movement to the pick, shall also cause a curvilinear movement of said pick, substantially as is herein specified.

2. The platform N, provided with the fixed gear-rim M, and turn-table O, substantially as and for the purpose specified.

3. The spring-arm U, when used in combination with the pick-shaft S, for the purpose of regulating the intensity of the blows given by the pick, substantially as is herein specified.

4. The combination of the pick-shaft S, with pick-arm Q and spring-arm U, cord or chain D, and lever

C, the several parts being arranged substantially as and for the purpose specified.

5. The arrangement of the shaft F provided with pinion L and worm-wheel G, in the standards E l, so that it may be slid up and down, for the purpose of throwing said pinion and worm-wheel out of gear with the fixed gear-rim M and worm h, substantially as is herein specified.

6. The combination of the pick-shaft S, provided with pick-arm Q and tilting-arm T, fly-wheel J with tappets b b, shaft H with worm h, shaft F with worm-wheel G and pinion L, and fixed gear-rim M, the several parts being arranged substantially as and for the purpose specified.

7. The combination of shaft H provided with the crank I and fly-wheel J, with tappets b b, pick-shaft S with pick-arm Q, tilting-arm T, and spring-arm U, cord or chain D, and lever C, the several parts being arranged substantially as and for the purpose specified.

8. The combination of the fixed gear-rim M, shaft with pinion L and worm-wheel G, shaft H, with worm h, and fly-wheel J with tappets b b thereon, pick-shaft S with tilting-arm T, spring-arm U, and pick-arm Q, cord or chain D, and lever C, the several parts being arranged substantially as and for the purpose specified:

As evidence that I claim the foregoing, I have hereunto set my hand, in the presence of two witnesses, this 4th day of August, 1869.

J. S. CARR.
